Jack K. La Trell, Glendale, Calif.

Application January 19, 1953, Serial No. 23,183

Term of patent 14 years

(Cl. D30—1)

To all whom it may concern:

Be it known that I, Jack K. La Trell, a citizen of the United States and a resident of Glendale, county of Los Angeles, California, have invented a new, original, and ornamental Design for an Air Pistol, of which the following is a specification, reference being had to the accompanying drawing, forming part thereof.

Referring to the drawing:

Fig. 1 is a side elevation of an air pistol, showing my new design;

Fig. 2 is a front end elevation thereof;

Fig. 3 is a side elevation looking towards the opposite side of that shown in Fig. 1;

Fig. 4 is a rear end elevation of the pistol;

Fig. 5 is a top plan view thereof; and
Fig. 6 is a bottom plan view.

I claim:
The ornamental design for an air pistol, as shown.
